CONTROL DEVICE FOR DENTAL ENGINES
AND THE LIKEHarold M. Keckley, Dayton, Ohio, assignor, by
direct and mesne assignments, to Wm. O. Ballard, Toledo, Ohio

Application December 28, 1946, Serial No. 718,950

3 Claims. (Cl. 318—349)

1

This invention relates as indicated to a novel control device for dental engines and the like, and more particularly to a foot operated control device adapted to permit considerable freedom of movement on the part of the operator.

It has been conventional to provide foot operated switches for various types of power driven tools such as dental engines in order that the operator may have both hands free to handle the tool or work. In the case of dental engines of the type wherein a tool such as a drill is driven by a motor supported on a column adjacent the dental chair, a switch is ordinarily provided on the floor adjacent the base of such chair and the dentist operates the drill by moving the lever of such switch with his foot, the motor stopping when his foot is removed. Such an arrangement, while freeing the dentist's hands, has proven very awkward and inconvenient in other ways. To operate such switch it has been necessary for the dentist to stand with all or most of his weight on one foot, resulting in the development of a very bad posture, particularly in the tipping of the pelvis, which in time may reach the importance of an occupational disease. Also bad cases of varicose veins often develop in the ankle on which the weight is carried. The dentist must frequently shift his position about the chair and patient while working, and since he must keep his foot upon the switch at all times if the operation of the tool is not to be interrupted, he generally finds some difficulty in thus moving about the chair, this necessitating frequent movement of location of such foot controlled switch.

It is therefore a primary object of this invention to provide a novel control device for dental engines and the like which will permit a proper and comfortable posture of the operator while operating the same and will facilitate his movement about the chair by eliminating the necessity of shifting the location of the foot control means when he changes position while working on the patient.

Another object of this invention is to provide a floor mat in which means to operate such device is incorporated.

Still another object is to provide mechanism whereby the operator may readily change the speed and direction of rotation of the motor driving the tool.

A further object is to provide a support for the tool so arranged that the motor can not be started while such tool rests on such support.

To the accomplishment of the foregoing and related ends, said invention, then, consists of the

2

means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawings—

10 Fig. 1 is a general perspective view of a dental chair and dental engine associated therewith showing a preferred arrangement of the new control device;

Fig. 2 is a sectional view through the new floor mat taken along the line 2—2 on Fig. 1;

Fig. 3 is a side elevational view, partly in section, of the control mechanism shown installed in the base of the usual tool supporting column;

Fig. 4 is an end elevational view of such mechanism;

Fig. 5 is a top plan view of such mechanism;

Fig. 6 is a fragmentary detail of the pawl adapted to operate the speed control ratchet;

Fig. 7 is an enlarged detail view of the speed control switch operating means; and

Fig. 8 is a wiring diagram of the various control circuits.

Referring now more particularly to the annexed drawings and especially Figs. 1 and 2 thereof, the control mechanism of the invention is adapted to be installed in the base 1 of the column 2 which carries the motor 3 adapted to drive the drill or other dental tool 4 through a flexible shaft or endless belt arrangement 5. The tool 4 may be hung when not in use from a hook 6 mounted for slight pivotal movement in a vertical plane on column 2. Incorporated in a molded rubber mat 7 shaped to conform to the base 8 of the dental chair 9 is an elongated tubular member 10 closed at one end and with the other end 11 extending beyond such mat. This tubular member is resiliently compressible by foot pressure of the operator whereby fluid pressure may be developed in such extended portion. While such member will ordinarily be oil-filled it may contain other fluids such as water, air, etc., if desired.

Referring now to Figs. 3 to 7 inclusive, there is installed in the base 1 of the column a chamber 12 with which such extension 11 of tubular member 10 communicates. A fluid pressure diaphragm 13 in the upper portion of such chamber carries an upwardly directed finger 14. Such finger engages the end portion of element 15 of master switch 16, such element being normally slightly

spaced from contact 17 of such switch. When the diaphragm 13 is moved upwardly under the influence of fluid pressure such element will be caused to engage such contact, thereby closing such switch.

Mounted on the upper surface of the chamber 12 is a frame member 18 supporting a solenoid 19. Journalled in a vertically extending plate member 20 also carried by such chamber is a shaft 21 having a ratchet 22 on that portion extending adjacent solenoid 19. Flanges 23 and 24 depend from frame member 18 additionally to support such shaft. A pawl 25 is pivotally mounted on the end of an armature 26 supported in a slotted depending tongue 27. A spring 28 attached to the other end of such armature operates normally to hold such pawl out of engagement with the ratchet. A compression spring 29 tends to tilt such pawl outwardly relative to the armature 26 so that such pawl will not engage the teeth of the ratchet should it be moved upwardly through actuation of the armature against the force of spring 28.

A second solenoid 30 is mounted on top of frame member 18 which also carries an armature 31 normally held outwardly from the mechanism through the action of spring 32. The lower end of such armature 31 carries a link 33 pivotally connected to pawl 25. Thus on actuation of solenoid 30, armature 31 will be pulled inwardly causing pawl 25 to be swung into position to engage the teeth of ratchet 22.

Also keyed to shaft 21 to either side of plate 20 are cams 34 and 35 adapted when rotated to operate switches 36, 37 and 38. As shown in Figs. 7 and 8, cam 34 has eight lands and notches and cam 35 has eight lands and notches spaced at different intervals. These cams are keyed to shaft 21 in such relation to each other that upon rotation of such shaft switches 36, 38, and 37 may be sequentially opened and then closed again in reverse order.

The operation of the mechanism may best be understood by reference to Fig. 8 of the drawing. When the dental tool is lifted from its support 6, such support will be pivoted upwardly under the influence of spring 39 to engage contact 40. It will thus be seen that the motor 3 cannot be started until such tool has been lifted from its support. Stepping on tube 10 actuates diaphragm 13 to close switch 16, thereby starting the motor. Such motor is provided with a reversing switch 41 whereby the direction of rotation of the tool may be reversed. As shown diagrammatically in Fig. 8, this switch in reality comprises two single pole double throw reversing switches adapted to be simultaneously operated. It will desirably be set in the mat 1 where it will be within convenient reach of the foot of the operator.

In parallel with such main motor circuit is a circuit including solenoid 30, a resistance 42, and a one-half wave rectifier 43. The effect of such rectifier is to convert such parallel circuit to direct current. Shunted across such circuit adjacent solenoid 30 is a capacitance 44 which cooperates with resistance 42 to cause a delay of approximately one-half second in the operation of solenoid 30.

Thus, when the motor circuit is closed as above-described, solenoid 19 will be activated to move armature 26 with pawl 25 upwardly, but such pawl will not operatively engage ratchet 22 in view of the above-indicated delay in the activation of solenoid 30 which is operative to move pawl 25 into ratchet engaging position. The motor will

therefore operate at whatever speed it was operating at when last stopped. The circuits including switches 36, 38 and 37 are provided with resistances 45, 46 and 47 respectively bridging the motor circuit in the same manner as main motor resistance 48.

Assuming that cams 34 and 35 have been left in such positions that switches 36, 38 and 37 are all closed, it will be obvious that the motor will be 10 operating at slowest speed. Now, if the operator removes his foot momentarily from tube 10, main switch 16 will be opened, deactivating solenoid 19 and permitting armature 26 and pawl 25 to swing away from ratchet 22. Due to the delay in the 15 deactivation of solenoid 30 however, armature 31 will not be at once released, and pawl 25 will remain drawn into ratchet engaging position. If the operator will now again step on tube 10 to close switch 16 before solenoid 30 releases armature 31, the reactivated solenoid 19 will cause 20 pawl 25 to turn ratchet 22, thereby opening switch 36. The motor will therefore operate at its next highest speed. This operation may be repeated, sequentially opening switches 38 and 37 until the 25 motor is operating at its highest speed. Further rotation of ratchet 22 will then sequentially close such switches in reverse order, reducing the speed in the same sequence. It is obvious that such mechanism provides means whereby the operator 30 has the speed of his motor driven tool under quick control at all times.

It will be seen from the foregoing that there is provided a novel control device for dental engines and the like which affords quick and precise control over the operation of such engine while at the same time permitting considerable freedom of movement on the part of the operator. While described in association with a dental engine, it is readily apparent that the control means of the 40 invention is adapted to be employed in conjunction with many types of machine tools where a certain amount of freedom of movement is desirable on the part of the operator and where he requires the use of both hands in handling the work for example. As a further result of the invention, the operator is enabled to stand in a much more comfortable position, is less subject to fatigue, and maintains a better posture.

Other forms may be employed embodying the 45 features of our invention instead of the one here explained, change being made in the form or construction, provided the elements stated by any of the following claims or the equivalent of such stated elements be employed.

I therefore particularly point out and distinctly claim as my invention:

1. Electric motor speed change means comprising a resistance shunted across such motor circuit, a switch operative to open and close 60 such shunt circuit, a ratchet, a pawl operative to drive said ratchet, a solenoid operative to move said pawl to turn said ratchet, a spring adapted to hold said pawl out of ratchet-engaging position, a second solenoid operative to move said 65 pawl against the force of said spring into ratchet-engaging position, delay means associated with said second solenoid operative to delay energization of said second solenoid until after said first-named solenoid has been energized and to continue energization of said second solenoid for a designated time interval after de-energization of said first-named solenoid, whereby said pawl will be able operatively to engage said ratchet upon first energizing said solenoids but will operatively engage said ratchet upon re-energiza-

tion of said solenoids within such time interval, and means actuated by rotation of said ratchet operative to open and close said switch.

2. Electric motor speed change means comprising a plurality of resistances shunted in parallel across such motor circuit, a switch for each such shunt circuit operative to open and close such shunt circuits individually, a ratchet, a pawl operative to drive said ratchet, a solenoid operative to move said pawl to turn said ratchet, a spring adapted to hold said pawl out of ratchet-engaging position, a second solenoid operative to move said pawl against the force of said spring into ratchet-engaging position, delay means associated with said second solenoid operative to delay energization of said second solenoid until after said first-named solenoid has been energized and to continue energization of said second solenoid for a designated time interval after de-energization of said first-named solenoid, whereby said pawl will be unable to operatively engage said ratchet upon first energizing said solenoids but will operatively engage said ratchet upon re-energization of said solenoids within such time interval, and cam means actuated by said ratchet operative to open and close said switches in desired sequence.

3. Electric motor speed change means comprising a resistance shunted across such motor circuit, a switch operative to open and close such shunt circuit, a ratchet, a pawl operative to drive said ratchet, means adapted to move said pawl to drive said ratchet, means operative to

5 keep said pawl from operatively engaging said ratchet when thus moved, means operative to overcome said last-named means and move said pawl into ratchet-engaging position, delay means operative upon energization of the circuit including said pawl operating and control means to delay operation of said means operative to move said pawl into ratchet-engaging position and upon de-energization of such circuit to continue to hold said pawl in ratchet engaging position for a designated time interval, whereby said pawl will be unable operatively to engage said ratchet upon first energizing such circuit but will operatively engage said ratchet upon re-energization of such circuit within such time interval, and means actuated by rotation of said ratchet operative to open and close said switch.
